ADJUSTABLE PANTS PRESSER

George G. A. Lauzon, Three Rivers,
Ontario, Canada

Application September 24, 1948, Serial No. 50,963

8 Claims. (Cl. 223—57)

1

This invention relates to an improved pants-pressing apparatus which is adapted for steam-pressing and drying pants.

The main object of my invention is to provide pants-pressing apparatus of the character indicated which are not only adjustable to almost any length and width of pants, but equipped to press both legs of a pair of pants individually and simultaneously.

Another object is to provide such an apparatus with means for steaming, pressing and drying the pants to be pressed.

A further object is to have a pressing apparatus of the mentioned class wherein an adjustable means serves to suspend the pants to be pressed in an inverted raised or lowered position with the leg portions disposed on both sides of a stationary steaming and heating member and exterior members serve to press the pants against the latter, while other adjustable means hold the waist portion of the pants in place with special means on the apparatus serving to press or form the waist portion simultaneously with the pressing of the leg portions.

It is also an object to dispose the pants-pressing apparatus in a vertical arrangement to render it convenient and accessible to use, to speed up operation and to occupy a minimum of floor space. The vertical arrangement particularly involves pressing the pants in inverted position so that the pockets thereof fall away from the legs of the pants and allow the latter to be pressed without the normal presence of the pockets with the result that the pockets are not pressed with the legs and do not leave pocket press marks on said legs.

A practical object is also to provide such an apparatus with various controls and means for initiating and terminating various stages of operation at will, as well as to embody a reasonably simple construction which will be certain to operate and not likely to get out of order.

Other objects and advantages of my invention will appear in further detail as the specification proceeds.

In order to facilitate ready comprehension of this invention for a proper appreciation of the salient features thereof, the invention is illustrated on the accompanying drawings forming part hereof, and in which:

Figure 1 is a side elevation partly in section of a pants-pressing apparatus embodying the invention in a practical form;

Figure 2 is a front elevation of the same apparatus;

2

Figure 3 is a plan view of the apparatus of Figures 1 and 2, as seen from the top of Figure 2;

Figure 4 is an enlarged front elevation of the heating and steaming member termed a "middle buck" of Figure 1, with portions broken away to disclose internal detail;

Figure 5 is a vertical section of the same middle buck as taken on line 5—5 of Figure 4;

Figure 6 is a transverse section of the same member taken on line 6—6 in Figure 4;

Figure 7 is an enlarged elevation of one of the side pressing members or side bucks of Figure 1, with portions removed to disclose internal detail;

Figure 8 is a plan view of the same pressing member as seen from the top in Figure 7;

Figure 9 is a transverse section taken on line 9—9 in Figure 7;

Figure 10 is a transverse section taken on line 10—10 in Figure 1;

Figure 11 is a side elevation of an inside cuff pants hanger on an enlarged scale which also appears in operative position in Figures 1 and 2;

Figure 12 is a front elevation of the same pants hanger illustrated in Figure 11.

Throughout the views, the same reference numerals indicate the same or like parts.

On conventional pressing machines and apparatus for pressing trousers, pants and the like, it is usual to lay the garment involved upon a horizontal pressing board and then fold down a hinged pressing board upon the garment, and when the latter has been pressed, the hinged pressing board is raised and the pressed garment released. Such apparatus may serve for certain purposes, but only one trouser leg is pressed at a time and the apparatus itself occupies a considerable width of floor space.

Now it has occurred to me that it should be possible to hang the trousers or pants and press the two legs simultaneously by a vertical arrangement of special pressing means to reduce the pressing time and also the floor space occupied by the apparatus as a whole. After duly considering this problem, I have succeeded in designing apparatus for the mentioned purpose in a manner to fulfill the foregoing objects, as will now be particularly pointed out and explained.

Hence, in the practice of my invention, and referring again to the drawings, the present pants or trouser-pressing apparatus, generally indicated at 14, includes a frame built up of two opposite base members 15, 15 (Figures 1 and 3) connected at the rear with a cross-member 16 and at the resulting rear corners having a pair of upper right posts in the form of channel members 17, 17

rising rigidly therefrom interconnected by a pair of spaced horizontal cross-members 18 and 19 to confer rigidity upon the resulting frame upon the rear of the frame, and extending at least down to the cross-member 19 is an upwardly-projecting pipe or hollow crane member 20 which has a forwardly-arcuate portion 21 terminating in an open downwardly-projecting end 22 serving a purpose which will presently be explained.

The first-mentioned horizontal spaced base members 15 may be channel members or angle irons from which a pair of angle irons 23, 24 project rigidly upward at the forward ends of said members 15, while a further pair of angle irons project upwardly from intermediate portions of said base members at 25, 26, the four upright members 23, 24, 25 and 26 forming corner supports for a blast chamber 27 having the sides and front thereof closed, as shown at 28, 29 and 30, for example. The rear of mentioned blast chamber is provided with an open frame 31 to which is attached a fan chamber 32 containing a fan 33 mounted on a motor shaft 34 of an electric motor 35, which is supported upon a base 36 and held in position by bolts 37 or the like. The motor is connected to a power means by means of the conductors in a conduit or pipe 38 communicating with the motor inlet 39, while from the inlet box 39 connections run forwardly through the conduit 40 to a switch 41 mounted upon the blast chamber for turning the current on or off to start or stop the fan as may be required during operation.

Returning again to the frame of the machine, and particularly the uprights 17 and the cross-pieces 19 and 18, it may be stated that preferably the pipe 20 extends down through the latter and may be brazed or welded thereto in order to hold the pipe firmly in place with its overhanging crane portion 21 spaced apart upon pipe 20, and between the two cross-bars 18 and 19 are a pair of forwardly-projecting supports 42, 43 which are reinforced by collars 44, 45 which may be brazed or welded upon pipe 20 in order to secure them in place. The supporting members 42 and 43 project forwardly in horizontal spaced relation and are brazed or welded to an inclined metal bar 46 of a stationary intermediate steaming and heating member or buck 47, as best seen in Figures 4, 5 and 6.

The mentioned intermediate stationary buck just referred to comprises a pair of sheet metal members or plates 48, 49 spaced apart by a plurality of blocks 50, 50, etc., distributed between them in spaced-apart relation and being integral with a rear wall 51 which is forwardly inclined in the upward direction and to which the bar 46 is bolted by a plurality of bolts 52, 52. At the top and bottom, as well as the forward ends of these plates 48 and 49 they are bent inwardly toward each other to form overlapping end walls 53, 54 at the bottom, 55, 56 at the top, and at the forward portion the overlapping upwardly and rearwardly-inclined front walls 57 and 58, these walls being secured together by rivets or screws 59, 59, etc., so that their overlapping portions hold the forward and rear walls 48 and 49 in a rigid unit which is hollow like a flat box, as it were, and rigidly supported on the forwardly-extending supports or arms 42 and 43 secured to rear pipe 20. Thus, the end walls 54 and 56 constitute the bottom and the top portions of the buck 47, it being evident that the top 56 is considerably narrower than the bottom 54, while an intermediate portion of the bottom is arched upwardly to form a curved clearance portion 60 for a purpose which will later be

explained, with a rear and front wall 51, 58 converging upwardly toward each other and the two walls 48 and 49 provided with a large number of small apertures 61, 61 through which steam and heated air are intended to escape into the garment to be pressed, as will later appear. In order to provide this buck 47 with steam, a steam pipe 62 provided with a valve 63 is connected with a boiler or steam supply, not shown, and extends upwardly behind the previously-described frame at 64, terminating in the upper end in a T 65 from which a forwardly-projecting pipe 66 extends to the lower portion of buck 47, being provided in an intermediate position with a quick-acting valve 67 having an operating lever 68. Beyond this valve the pipe continues as pipe 69 entering through a collar 70 upon the rear wall 51 of buck 47. Within the latter the pipe continues as a perforate pipe 71 to which are connected two upwardly-projecting perforate upright pipes 72, 72 terminating in blind ends at the upper portions thereof, the pipes 71 and 72 being pierced on all sides by a large number of perforations 73, 73, etc., so that live steam from the steam-supply pipe 62 may enter the interior of the buck through the perforations in the mentioned pipes and escape from the interior of the buck through the previously-mentioned perforations 61, 61 in the side plates 48 and 49 of this buck into the garment which may be in contact therewith, as will be more particularly described later on. In addition to the foregoing, means are included to heat the buck so that when the garment has been steamed it may thereafter be heated and dried by heat while still remaining in position. The buck is heated so that when live steam is introduced therein, this steam will not be condensed by contact with a cold buck.

Thus, to the steam-supply pipe 62, which receives its supply of steam from the boiler (not shown), is connected a valve 63 which connects through a short pipe 63' with a T 74, to which in turn is connected a pipe 74' also connected to a T 75. The latter has a pipe 76 connected thereto with a further T 65 connected to the upper end, while to this T is connected elbow 77' having a pipe 77 connected thereto and extending toward the stationary middle buck and through wall 51 into the latter. Within this buck the pipe is continued upwardly and downwardly through a group of loops 78, 79, 80, 81, 80' and 78' and issues from the buck through wall 51 again as return pipe 82 which through elbow 82' connects with the descending pipe 83. At the lower end, this pipe connects by way of elbow 83' with pipe 84 provided with check valve 85 which connects through T 86 and T 87 with descending pipe 88. The latter connects through elbow 88' with bottom pipe 89 which connects through elbow 89' with water collector 90 provided with pipe 91 connecting the collector with the boiler. The T 74 is interconnected with T 87 through a pipe 75', check valve 86' and further pipe 87' and thereby provide a valve-controlled connection between the steam-supply and return systems.

In following through the passage of the live steam through the stationary middle buck, it is, of course, obvious that the steam supply enters pipe 62 from the boiler and, passing through valve 63, reaches T 74 through short pipe 63' and then rises through pipe 74' to and through T 75 into pipe 76 and up through T 65 to elbow 77'. From the latter the steam travels through pipe 77 in through wall 51 into the left side or end of 75 the middle buck, as may be seen in Figure 4.

Within buck wall 51 the steam rises to the top of the buck into the inner loop 78 and there turns down to descend through the bottom loop 79, whence the steam rises again to the top to loop 80, from which it descends within buck walls 51, 58 to the bottom return loop 81. Upon entering this loop, the steam is returned upward to the upper loop 80' in the top of the buck from which it again descends to inner bottom loop 79', and then again rises to the top into upper loop 78'. From this upper loop the steam finally descends within wall 51 to pipe 82 through which it passes out through this wall to elbow 82' and then down in pipe 83 and by way of elbow 83' to pipe 84. Thereafter the steam passes through valve 85, through T 86, T 87 and elbow 88' and pipe 89 and elbow 89' into water collector 90, from which the steam returns to the boiler through pipe 91. As the heating of the buck by the means just outlined is intended to be a constant feature during operation, valve 63 suffices to turn the steam on which remains on during the entire course of the operation which thus does not require a service valve which requires to be turned on and off frequently in the course of the day. It has been mentioned that the steam issuing from the perforations 73, 73 in the perforate pipes 11 and 12, 72 tends to escape through the perforations 61, 61 in the two side plates 48 and 49 of the buck 47, but this is not strictly true in the fullest sense, because at the lower end of this buck is connected a suction pipe 92 in the wall 51 thereof for the purpose of withdrawing damp heated air from the buck and from the garment outside the latter, so that in large measure the heating and pressing operation includes also drying of the garment on the buck by the withdrawal of the moisture from the garment inwardly through the mentioned perforations 61, 61 in the two side plates of the buck. The suction pipe 92 is provided exteriorly of the buck with a quick-acting valve 93 having an operating lever 94, and like valve 67, being controlled in a manner which will presently be explained. The suction tube or pipe 92 beyond valve 93 connects with suction pump or vacuum tank or the like of more or less conventional construction and therefore superfluous to show, so long as reference thereto has been made.

While on the subject of steaming and steam heating of the garment to be pressed upon the apparatus, it may well serve to return to the motor 35 with its fan 33 within fan chamber 32, and its operation with respect to the blast chamber 27. In the rear of this chamber adjacent the fan 33 is located a closure or shutter system including a series of shutter slats 95, 95, etc., pivotally mounted at 96 on open frame 31 between the blast chamber and the fan housing 32 at the rear ends of these shutter members, while at their forward ends they are hinged to a vertical operating bar 97 connected at the upper end thereof to a link 98 by means of a ball-and-socket connection 99, this link being connected at the other end by a second ball-and-socket connection or joint to an eccentric portion or lever 101 at the rear end of a semi-rotary shaft 102 supported by a plurality of bearings in the upper part of the blast chamber indicated at 103 and terminating forwardly and exteriorly of the blast chamber in a handle 104 by which to turn the shaft 102 and thereby raise or lower the vertical operating bar 97 and thereby also raise and open the slats 95, 95 of the shutter structure or close the same down in front of the fan 33. Of course, a lever could be substituted for shaft 102 pivotally mounted within the walls of the blast chamber

and the rear end thereof connected to the vertical operating bar 97 if so desired, or any other construction for operating bar 97 may be used.

Spaced slightly forward of the shutter structure just described is a vertically-disposed radiator 105 connected at the upper end thereof to a pipe 106 which in turn connects by means of the T 75 with pipe 64 previously described, and at the lower end, the radiator has an outlet pipe 108 connected by a pipe 109 and a check valve 110 to the T 88 previously mentioned as connecting the lower T 87 with the pipes 88 and 89 communicating with the liquid receiver 90 which in turn is connected by pipe 91 to the return of the boiler. Thus, the heat produced by the steam passing up from supply pipe 62 and pipe 64 through pipe 106 to the radiator 105 will be carried into the blast chamber by fan 33 when motor 35 is operating, and the blast from the fan will be controlled by the shutter structure which in turn is controlled by handle 104 on the front of the apparatus, the shutter members 95, 95 controlling the amount of air being driven in by fan 33 past radiator 105 into the blast chamber 27.

The blast chamber 27 is roofed over by a plurality of converging top walls 112, 113, 114, 115 which terminate at their inner ends in an upwardly-directed narrow chimney or neck which is elongated from front to back, but narrow transversely. To the upper portion of the neck or chimney 116 is attached a fabric bag 117 opening down into the chimney 116 and secured to the latter within the same by a narrow neck portion 118, while the upper portion of the bag has a cleft 119 into which the previously-described fixed buck 47 extends a limited distance downward, the cleft separating the upper portions of the bag into two side members 120, 121. The narrowed or neck portion 118 of the bag is preferably of fabric known as Celanese, and is attached in any known manner to the neck portion 116 of the blast chamber, as for example, by having the ends sewed to a metal wire or band and the same attached within said neck portion or chimney 116, or in any other manner which suggestss itself to any person skilled in the art, the purpose being to receive the blast of heated air in chamber 27 originating from fan 33 past radiator 105 and up through the neck portion 116 into the bag 117. The latter is intended to be inserted in the waist portion of a pair of trousers when inverted and mounted upon the apparatus for pressing, two further features being associated with the mentioned Celanese bag and the upper portion of the blast chamber.

The first of the mentioned features is that the same steam pipe 106 which supplies the upper end of radiator 105 with steam is continued into the center upper portion of the blast chamber by pipe 122, this pipe connecting by an elbow 123 with a quick-acting valve 124 operated by lever 125 connected to the inner or rear end of a manually-slidable plunger 126 exposed upon the forward portion of the neck member 116 of the blast chamber. Extending upwardly from the mentioned valve 124 is a steam nozzle or nipple 127 directed upwardly into the neck 116 for introducing steam into the heated air which is received from the blast chamber 27. The heated air received from the blast chamber as propelled into the same by the fan 33 is, of course, intended to be directed upwardly through the neck portion 116 into the fabric bag 117 to balloon the same within the waist portion of the trousers or pants to be pressed, while the plunger 126 may be

operated to open valve 124 and thereby cause steam to escape from nozzle 121 to mix with the heated air and thereby promote the pressing of the waist portion of the trousers by ballooning that portion, it being also the intention that the trousers will have the upper portions 120, 121 extending a very short distance into each of the trouser legs of the pants to be pressed, as will be pointed out in further detail when the manner of suspending the trousers is discussed.

The other feature associated with the bag 117 and the neck portion 116 of the upper blast chamber concerns the fitting of the waist portion of the trousers about the bag and fastening the trousers below the latter. For this purpose a rear waist holder 128 is provided with a rear bowed portion 129 adapted to fit within the rear portion of the waist of a pair of trousers to be pressed, to the forward ends of the bowed portion just mentioned, a pair of forwardly-extending side bars 130 and 131 are rigidly connected and rearwardly slidably supported in a pair of bearings 132, 132 fixed upon the sides of the neck portion or chimney 116, while at their forward ends the side bars 130 and 131 are connected in a unit by the transverse handle member 133. Upon the lower edges of the forward portions of the mentioned side bars, the latter are serrated, as indicated at 134, adapting them to engage with a pair of side struts 135, 135 fixed upon the forward portions of the sides of the chimney member 116, with the result that by manipulating the handle portion 133 and raising the forward portions of the side bars, the latter may be adjusted rearwardly or forwardly according to the width of the trouser waist to be accommodated at the rear.

In similar manner, a second waist holder 136 is supported slidably in a channel member 137 fixed to the forward end of the chimney 116 by brazing or welding, or the like, the forward end of this member 136 having a bowed or arcuate strip 138 adapted to fit within the forward portion of the trouser waist, while the side edges of the holder are serrated in order to adapt the member to be adjustably shifted and located in the channel member in engagement with the inner side projections 139 thereof according to the desired position of the bowed strip 138 determined by the size of the waist to be engaged thereby. At the forward end, the second waist holder 136 may be provided with a depending handle 140 by which to manipulate it and adjust it in position.

At this point it may be well to consider the means by which the trousers or pants are suspended with the trouser legs on opposite sides of the stationary middle buck 47 before proceeding to describe the two outer movable bucks that cooperate with it. Extending upwardly through the pipe 20 and its overhanging portion 21 is a flexible cable terminating at the lower end in a pivotal connection 142 to which is connected the outer end of a lever or arm 143 fixed upon the rear end of a shaft 144 supported in bearings 145 upon the side wall 28 of the blast chamber 27 and upon the forward end in front of the latter chamber provided with a rigidly-mounted pedal 146 by which to partly rotate shaft 144 and thereby lower the lever 143 and draw the cable 141 down into the pipe 20 in such fashion as to raise the upper forward end of this cable, as will now be explained. At the forward end 22 of the arcuate pipe portion 21, the cable 141 is preferably bifurcated to form the two ends 147, 147, each of which terminates in

5 a ring 148 for suspending a special hanger therefrom, so that two hangers are thus hung side by side from suspension rings 148, 148. Upon the rings 148 are suspended the hanger hooks 149, 149 of a pair of hangers 150, 150. Each hanger includes an upper arcuate portion 151 having a lower shoulder portion 152 projecting outwardly therefrom on one side and from the outer end of said shoulder portion 152 depends 10 a rigidly-attached internal cuff-engaging portion 153 having the outer edge 154 serrated or roughened in order to insure that friction will occur between member 153 and the interior of the cuff or lower end of the trouser leg upon one side thereof. At the upper portion of the arcuate section 151 of each hanger upon the other side is pivotally connected an upwardly-extending limb 155 by means of a pivotal connection 156, while the lower portion of member 155 is sharply bent outwardly in a forward direction at 157 to form a second shoulder portion terminating at the end in a depending inside cuff-engaging member 158 with serrations or teeth 159 on the outer edge thereof and thus resembling the previously-mentioned cuff-engaging portion 153. Between the members 151 and 155 of the hanger in each case is secured a leaf spring 160 which tends to urge these members apart upon pivot mounting 156, while between these members is also located a limiting rod 161 forming by its end heads 162, 163 a stop which prevents members 151 and 155 from separating more than a predetermined distance under bias of spring 160. It is thus clear that spring 160 tends to urge members 153 and 158 apart and cause the roughened or serrated portions 154 and 159 thereof to engage in the opposite sides of the interior of a trouser cuff. The arrangement is such that each hanger is intended to engage in one of the two trouser legs independently of the other, spring 160 serving to hold members 153 and 158. When one of these hangers is to be inserted in the trouser leg, the members 153 and 158 are, of course, first forced 15 toward each other manually and inserted in the interior of the trouser cuff or leg and then released within the latter so that the edges 154 and 159 thereof engage by friction within the collar or trouser leg and due to the bias of spring 160 the inside cuff-engaging members 153 and 158 will therefore hold the trouser leg at the bottom part thereof in a tensed condition from within, and when both trouser legs are similarly suspended upon opposite sides of the stationary buck 47, the waist portion of the trousers or pants will extend down about the fabric bag 117, while the edge of the waist is engaged by the bowed portions 129 and 138 of the two waist holders 128 and 136. The limiting bars or rods 161 naturally extend through side apertures in members 151 and 155 and serve only to prevent the inside cuff-engaging members 153 and 158 from being expanded too widely only in idle position, when no trousers are engaged thereby.

60 15 In order to cooperate with the stationary steam-heated buck 47, the apparatus is provided with a pair of outer movable bucks 164, 165 which are both pivotally mounted or supported upon the previously-described, forwardly-extending, rigid arms 42 and 43 supporting the stationary buck 47. For this purpose both of the latter members 42 and 43 are provided upon the sides thereof of adjacent to the rear pipe or post 20 with reinforcing side blocks 166, 167 65 secured thereto by screws or rivets 168, etc., while 70 75

through both arms extends a vertical pivot shaft 169. Upon this pivot shaft is mounted a pair of fixed collars 170, 171 at the ends thereof, and immediately within these collars are mounted rear bearing portions 172, 173, and extending from there are a pair of supporting arms 174, 175 to which the buck 164 is attached, as will now be detailed. As best shown in Figures 7 and 8, as well as 9, this side buck 164 primarily includes a rigid metal frame 176 which is substantially the same shape and coextensive with the previously-described rigid middle buck 47, the frame consisting of the upwardly-converging side members 177, 178, a short top member 179 and the relatively longer bottom member 180, these members being welded or brazed together to form a rigid frame. To the side members 177 and 178 are welded the ends of a pair of outwardly-bowed or arched bars or rods 181, 182 and to the inside of both of these arcuate members is welded or brazed a vertical bar 183 to which the supporting arms 174 and 175 are brazed or welded for supporting this buck. The arms 174 and 175, at the points where they are secured to the vertical bar 183 just mentioned, are reduced to form the forwardly-extending lighter arm members 184, 185 to which a vertical handle 186 is attached by screws or bolts 187, 188. In addition, a pair of attachment members in the form of a pair of rods 188, 189 are brazed or welded to the interior of the bowed or arched members 181 and 182 in spaced relation within the side members 177 and 178 of the frame.

The entire frame is overlaid upon its flat inner side with a pad of cotton batting or flannel 190, and over this is applied a layer of fabric, such as celanese or any other suitable fabric 191, the sides of this fabric being brought in over the side portions 177 and 178 of the frame and formed into hems 192, 193 enveloping attachment rods 194, 195 occupying the interior of these hems, and upon these attachment rods 194 and 195 are applied a series of S hooks 196, 196, etc., upon each side of the buck, the other ends of these hooks being arranged to engage over the attachment rods 188 and 189 previously described. In the same way, the lower end of the fabric 191 is brought up outside of the lower frame member 180 and formed into a hem 197 about the rod 193 to which a pair of S hooks 199, 199 are attached at their lower ends, while the upper ends thereof are connected over the lower arcuate bar or rod 182 of the frame. At the top also the fabric is brought over the upper frame member 179 to terminate in a hem 200 containing an attachment rod 201 which is connected by a pair of further S hooks 199, 199 to the upper arcuate bar or rod 181 of the frame. In this fashion, all four sides of the fabric are held tight and anchored to the frame of the buck so that the inner side 202 of this buck is flat with the fabric and its underlying cushion 190 suspended across the open area in frame 176 and presenting the flat side against the left side of the rigid buck 47. The arrangement is such with regard to this left buck 164 that by manipulating handle 186 and drawing the same toward the left, the buck will be swung upon members 174 and 175 by the bearing 172 and 173 rotating about pivot shaft 169 in such fashion as to expose the left side or plate 48 of the middle buck 47.

The right buck 165 is of similar construction throughout to that already described in reference to the left buck 164, except that all parts are

reversed so that the right buck 165 serves to present its flat side toward the right side or plate 49 of the rigid center buck 47. Without going into too much detail regarding the right buck, it may be stated that it is also provided with outwardly-arched cross-rods 203, 204 forming portions of the frame thereof, and having a central vertical bar 205 welded or brazed thereto to which the handle members 206, 207 are permanently attached by brazing or welding, these handle members terminating forwardly at the vertical handle 208 attached thereto by which to manipulate the right buck 165. Rearwardly, the members 206 and 207 project as rear supporting arms 209, 210 terminating at the rear ends in bearing members 211, 212 mounted upon the vertical pivot shaft 169 which also supports the previously-described arms 174 and 175 of the left buck 164. The bearing members 211 and 212 are disposed between the rigid arms 42 and 43 which support the middle buck and pivotally support the buck 165 in such position as to be capable of being swung away from the middle buck 47 by means of handle 208 in the same manner as the handle 196 may be used to swing the left buck 164 away from the middle buck. The bearing members 172, 173, as well as 211 and 212, may well be ball-bearing members, or any other kind of bearing structures, facilitating easy swinging of the two side bucks to and from the middle buck during operation, and as such bearings are well known, it appears superfluous to illustrate the same in detail.

In order to complete the facilities for operation of the apparatus, it should be noted that the two pedals 213 and 214 are fixed upon the forward ends of shafts 215 and 216 provided at their rear ends with arms or levers 217 and 218 connected by long vertical links 219 and 220 to the operating levers 94 and 68 of valves 93 and 67 previously described.

In order to ensure that operation will continue without break-down or soiling the clothing to be pressed, plates 48 and 49 of center buck 47 may be made of stainless steel or of any other alloy or metal which resists oxidation or rusting, while it is optional to cover buck 47 with cotton batting, with flannel and further cotton batting, if desired. Thus covered, a more uniform and even distribution of steam results, and the pressed trousers or pants are prevented from becoming shiny and glossy. The steam pipes 82 and 87, which communicate with the interior of the buck for heating the same, may consist of copper tubing, if desired, and this is also true of the perforated steam pipes 71 and 72. In similar fashion, the walls of the blast chamber 27 may be made of stainless steel sheets or other rust-proof metals or alloys, and this principle may well refer to all the metal parts throughout the apparatus, even including the trouser hangers 150, and I prefer to be entirely unlimited with respect to the materials used so long as they are suitable for the purpose.

When a pair of trousers is to be pressed upon this apparatus, steam is first turned on by opening valve 63 and thereafter the switch 41 is closed to start the motor 35 rotating the fan 33, and the side bucks 164 and 165 are swung apart by means of handles 186 and 208 until they stand wide open from the stationary center buck 47, at which moment the pedal 146 is depressed by the foot outwardly toward the left side in order to raise the rear lever 143 and thereby lower the suspension rings 148 and with them

the pants hangers 150, 150. If deemed necessary, these hangers may be released momentarily from the suspension rings by unhooking their hooks 149 therefrom and each hanger inserted in the lower end or cuff of each one of the pairs of trouser legs so that they project equally therefrom with their upper arched portions 157, and then the trousers are put into position with one leg up on each side of the stationary buck 47, the crotch of the trousers being accommodated by the arcuate cutout portion 60, best shown in Figure 4, and both of the hangers 150 hooked on rings 148 so that the pants are suspended on both sides of the middle buck. Thereafter, the waist portion of the trousers is brought down about the fabric bag 117 with the two upper divided portions 120 and 121 projecting slightly up into each of the trouser legs, and then the two waist holders 128 and 136 are adjusted apart to fit the interior of the waist portion. Subsequently, the foot is brought down on the pedal 146 again toward the right in order to lower lever 143 and thereby raise the two hangers just sufficiently to allow the trousers to lie flat upon the center buck, and finally, by using handles 186 and 208, the side bucks 164 and 165 are swung together upon the trouser legs and the trousers or pants are in position for the pressing operation. The plunger 126 is pushed to open valve 124 and thereby inject steam up into the fabric bag 117 and at the same time the handle 104 is manipulated to open the shutter slats 95, 95 to desired extent in order to propel heated and humidified air from the radiator 105 and past the nozzle 127 up into the mentioned bag in order to steam the waist of the trousers, whereupon the foot is brought down on the extreme right pedal 214 in order to lower the lever 218 thereof and with it the link 220 in order to open the upper valve 67 and cause steam to enter pipe 69 and thereby introduce steam into the interior of the center buck 47, in the meantime, the handles 186 and 208 controlling the side bucks 164 and 165 being held in position with the bucks in contact with the trouser legs. When the steaming has been completed—in fact while it is still in progress—the foot is brought down on the second pedal toward the right 213 in order to lower the lever 217 thereof and with it the link 219 to the second valve 93 in order to cause suction through pipe 92 to withdraw the humid air from within the center buck until all of the steam is removed and the pants are substantially dry, the valve 124 being in the meantime also closed by withdrawing plunger 126 and by the foot closing valve 67 by applying the foot to the right side of pedal 214. After the steaming and the drying have been completed, the trousers are pressed and may be removed by opening the side bucks by means of handles 186 and 208 and the foot applied to the left side of pedal 146 in order to raise the rear lever 143 thereof and thus lower the hangers 150 so that they may be unhooked from rings 148. After the trousers have thus been released from the supporting rings, they may be removed from the center buck and then the hangers themselves removed from the lower cuff portions of the trouser legs and the latter then either laid out or hung up until called for by the patron who has left them for pressing. Naturally, variations in the above-mentioned method of using the apparatus may be applied by the user as desired, the time of the various operations being acquired by experience are nonetheless quite simple so that a pair of pants may be readily pressed by the apparatus in a very short time.

Manifestly, variations may be resorted to and parts and features of this apparatus may be modified or used without others within the scope of the appended claims.

Having now fully described my invention, I claim:

1. A pants presser including a frame having an upwardly-extending rigid member, a supporting arm projecting rigidly forward from the rigid member, an upright flat hollow frame fixed upon the supporting arm and having perforate sheet metal sides to form a stationary middle buck, a pivot mounting upon said supporting arms, a pair of swinging arms independently supported upon the pivot mounting, a pair of upright movable frames individually supported upon the swinging arms upon both sides of the stationary middle buck to form side bucks cooperating therewith, handles upon the movable frames or side bucks for swinging the latter against or away from the perforate sides of said middle buck, each side buck having a substantially flat side carrying a fabric cover presented toward the respectively-adjacent perforate side of said middle buck, heating means and a perforate steam pipe located within said middle buck, control means including a valve for controlling the flow of steam into said middle buck through said perforate steam pipe, and a supporting member fixedly mounted upon said upwardly-extending rigid member and projecting forwardly therefrom over said middle buck in a position to support a pants hanger thereover with the legs of the pants suspended at both sides of said middle buck in effective position to be pressed against the latter by said side bucks.
2. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings pivotally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric mounted upon the flat working side thereof with attachment means mounted upon the outer side for holding the edges of said fabric and thereby the fabric as a whole in place, a steam-heating pipe within said middle buck connected to an exterior source of steam supply, a perforate steam-supply pipe also mounted in the latter and externally thereof having an operative control valve, an accessible operating member for operating the control valve at will, a suction

pipe communicating with the interior of said middle buck having a further control valve and being connected to an outside source of suction, a second operating member connected to the further control valve for operating the latter at will, an overhanging supporting member rigidly mounted on said frame and terminating in a downwardly-directed end spaced above the top of the middle buck, and adjustable suspension means pendent from said end for supporting a 10 pair of pants hangers thereon in order to suspend the pants in inverted position with the two legs thereof disposed on the opposite sides of said middle buck in effective position to be pressed against the latter by said side bucks.

3. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings pivotally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric mounted upon the flat working side thereof with attachment means mounted upon the outer side for holding the edges of said fabric and thereby the fabric as a whole in place, the bottom of the middle buck having an intermediate upwardly-arched clearance portion for engaging against the crotch of the pants, a steam-heating pipe within said middle buck connected to an exterior source of steam supply, a perforate steam-supply pipe also mounted in the latter buck and externally thereof having an operative control valve, an accessible operating member for operating the control valve at will, a suction pipe communicating with the interior of said middle buck having a further control valve and being connected to an outside source of suction, a second operating member connected to the further control valve for operating the latter at will, a blast chamber fixed beneath the middle buck and having an upwardly-directed neck portion or chimney, a flexible porous bag connected to the latter for ballooning the waist of the pants to be pressed and having a pair of upwardly-projecting bag portions, a steam radiator in the chamber connected to the outside steam-supply source, a fan chamber connected to one portion of the blast chamber, a motor-driven fan rotatable in the fan chamber for driving air past the radiator to the neck portion in the flexible bag, manually-adjustable means for controlling the flow of heated air to said flexible bag, a pair of adjustable waist holders shiftably supported adjacent to said neck portion or chimney for engaging with the edges of the 70 waist of said pants, an overhanging hollow supporting member rigidly mounted on said frame and terminating in a downwardly-directed end spaced above the top of the middle buck, a cable in the supporting member having the upper end thereof projecting through said downwardly-directed end and terminating in at least one suspension ring for suspending therefrom one or more pants hangers and thereby suspending the pants in inverted position with the two leg portions thereof disposed on the opposite sides of

from said end for supporting a pair of pants hangers thereon in order to suspend the pants in inverted position with the two legs thereof disposed on the opposite sides of said middle buck in effective position to be pressed against the latter by said side bucks.

4. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings pivotally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric suspended on the inner side for holding the edges of said fabric and thereby the fabric as a whole in place, the bottom of the middle buck having an intermediate upwardly-arched clearance portion for engaging against the crotch of the pants, a steam-heating pipe within said middle buck connected to an exterior source of steam supply, a perforate steam-supply pipe also mounted in the latter buck and externally thereof having an operative control valve, an accessible operating member for operating the control valve at will, a suction pipe communicating with the interior of said middle buck having a further control valve and being connected to an outside source of suction, a second operating member connected to the further control valve for operating the latter at will, a blast chamber fixed beneath the middle buck and having an upwardly-directed neck portion or chimney, a flexible porous bag connected to the latter for ballooning the waist of the pants to be pressed and having a pair of upwardly-projecting bag portions, a steam radiator in the chamber connected to the outside steam-supply source, a fan chamber connected to one portion of the blast chamber, a motor-driven fan rotatable in the fan chamber for driving air past the radiator to the neck portion in the flexible bag, manually-adjustable means for controlling the flow of heated air to said flexible bag, a pair of adjustable waist holders shiftably supported adjacent to said neck portion or chimney for engaging with the edges of the 75 waist of said pants, an overhanging hollow supporting member rigidly mounted on said frame and terminating in a downwardly-directed end spaced above the top of the middle buck, a cable in the supporting member having the upper end thereof projecting through said downwardly-directed end and terminating in at least one suspension ring for suspending therefrom one or more pants hangers and thereby suspending the pants in inverted position with the two leg portions thereof disposed on the opposite sides of

said middle buck in effective position to be pressed against the latter by said side bucks, a shaft rotatably supported upon a portion of the blast chamber, a lever on one end of the shaft connected to the other end of said cable, and an operating member fixed upon the other end of said shaft for shifting said cable in said hollow support and thereby raising or lowering the suspension ring above the middle buck.

5. A pants presser including a frame having an upwardly-extending rigid member, a supporting arm projecting rigidly forward from the rigid member, an upright flat hollow frame fixed upon the supporting arm and having perforate sheet metal sides to form a stationary middle buck, a pivot mounting upon said supporting arm, a pair of swinging arms independently supported upon the pivot mounting, a pair of upright movable frames individually supported upon the swinging arms upon both sides of the stationary middle buck to form side bucks cooperating therewith, handles upon the movable frames or side buck for swinging the latter against or away from the perforate sides of said middle buck, each side buck having a substantially flat side carrying a fabric cover presented toward the respectively-adjacent perforate side of said middle buck, heating means and a perforate steam pipe located within the middle buck, control means including a valve for controlling the flow of steam into said middle buck, a supporting member fixedly mounted upon said upwardly-extending rigid member and projecting forwardly therefrom over said middle buck, a suspension member supported thereby over the latter, and a pair of pants hangers adapted to be suspended from said suspension member for supporting the pants in inverted position with the legs thereof suspended at both sides of said middle buck in effective position to be pressed against the latter by said side bucks, each pants hanger including a pair of upwardly-extending portions hinged together and having a leaf spring disposed between them biasing them apart, a limiting bolt or rod projecting through apertures in the lower portions of said members having heads upon the ends for limiting the outward movement of said members, a suspension hook projecting upwardly from one of said members, a pair of outwardly-projecting arms extending in opposite directions from the lower ends of said members and terminating in downwardly-projecting bars having the outer edges thereof serrated or roughened in order to promote friction between said bars and the inside portions of the cuffs or lower ends of the pants to be suspended and adapted to engage the trouser legs from within.

6. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings pivotally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the

perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric mounted upon the flat working side thereof with attachment means mounted upon the outer side for holding the edges of said fabric and thereby the fabric as a whole in place, the bottom of the middle buck having an intermediate upwardly-arched clearance portion for engaging against the crotch of the pants, a steam-heating pipe within said middle buck connected to an exterior source of steam supply, a perforate steam-supply pipe also mounted in the latter buck and externally thereof having an operative control valve, an accessible operating member for operating the control valve at will, a suction pipe communicating with the interior of said middle buck having a further control valve and being connected to an outside source of suction, a second operating member connected to the further control valve for operating the latter at will, a blast chamber fixed beneath the middle buck and having an upwardly-directed neck portion or chimney, a flexible porous bag connected to the latter for ballooning the waist of the pants to be pressed and having a pair of upwardly-projecting bag portions, a steam radiator in the chamber connected to the outside steam-supply source, a fan chamber connected to one portion of the blast chamber, a motor-driven fan rotatable in the fan chamber for driving air past the radiator to the neck portion and the flexible bag, control means including a group of pivotally-mounted slats arranged in a vertical series between the motor-driven fan and the radiator, an operating bar interconnecting the slats to open and close them simultaneously, a manually-operated member supported in the blast chamber with an externally accessible handle for manipulating the member at will, a lever on the latter member connected to said operating bar for opening or closing said slats from the last-mentioned handle, adjustable waist-holding means shiftably mounted adjacent to said neck portion for engaging within the edges of the waist of said pants, an overhanging supporting member rigidly mounted on said frame and terminating in a downwardly-directed end spaced above the top of the middle buck, and adjustable suspension means pendent from said end for supporting a pair of pants hangers thereon in order to suspend the pants in inverted position with the two legs thereof disposed on the opposite sides of said middle buck in effective position to be pressed against the latter by said side bucks.

7. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings pivotally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the

shaft and extending from the latter upon the other side of said middle buck, an upright movable frame fixed upon each pair of swinging arms and having a flat side thereon facing one of the perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric mounted upon the flat working side thereof with attachment means mounted upon the outer side for holding the edges of said fabric and thereby the fabric as a whole in place, the bottom of the middle buck having an intermediate upwardly-arched clearance portion for engaging against the crotch of the pants, a steam-heating pipe within said middle buck connected to an exterior source of steam supply, a perforate steam-supply pipe also mounted in the latter buck and externally thereof having an operative control valve, an accessible operating member for operating the control valve at will, a suction pipe communicating with the interior of said middle buck having a further control valve and being connected to an outside source of suction, a second operating member connected to the further control valve for operating the latter at will, a blast chamber fixed beneath the middle buck and having an upwardly-directed neck portion or chimney, a flexible porous bag connected to the latter for ballooning the waist of the pants to be pressed and having a pair of upwardly-projecting bag portions, a steam radiator in the chamber connected to the outside steam-supply source, driven means for propelling air past the radiator to the neck portion into the flexible bag, an upwardly-directed steam nozzle in the blast chamber within the neck portion or chimney thereon, a pipe connecting the steam nozzle to the outside steam-supply source, a valve between the latter pipe and said steam nozzle, a valve-operating member on said valve, a manually-operated member connected to the valve-operating member and extending through said chimney into accessible position upon the forward portion of the presser, manually-controlled adjustable means for controlling the flow of heated air to said flexible bag, a pair of adjustable waist holders shiftably supported adjacent to said neck portion or chimney for engaging within the edges of the waist of said pants, an overhanging supporting member rigidly mounted on said frame and terminating in a downwardly-directed end spaced above the top of the middle buck, and adjustable suspension means pendent from said end for supporting a pair of pants hangers thereon in order to suspend the pants in inverted position with the two legs thereof disposed on the opposite sides of said middle buck in effective position to be pressed against the latter by said side bucks.

8. An adjustable pants presser including a frame having an upwardly-extending rigid member, a pair of supporting arms projecting rigidly forward one above the other from the rigid member, an upright flat hollow frame fixed upon the supporting arms and having perforate sheet metal sides to form a stationary middle buck, a pivot shaft extending vertically through both supporting arms, a pair of swinging arms spaced apart one above the other having bearings piv-

otally mounted on the pivot shaft and extending from the latter upon one side of the middle buck, a second pair of swinging arms similarly spaced apart having bearings pivoted upon said pivot shaft and extending from the latter upon the other side of said middle buck, an upright movable frame fixed upon each pair of swinging arms and having a flat side thereon facing one of the perforate sides of said middle buck to form side bucks cooperating therewith, a pair of handles individually connected rigidly to the side bucks for swinging the latter toward and away from said middle buck, the latter and the side bucks being wider at the bottom than at the top and having their forward and rear edges converging toward the top and each side buck having a padded fabric mounted upon the flat working side thereof with attachment means mounted upon the outer side for holding the edges of said fabric and thereby the fabric as a whole in place, the bottom of the middle buck having an intermediate upwardly-arched clearance portion for engaging against the crotch of the pants, a steam-heating pipe within said middle buck connected to an exterior source of steam supply, a perforate steam-supply pipe also mounted in the latter buck and having a pair of branch perforated pipes projecting upwardly into the same and externally thereof having an operative control valve, an accessible operating member for operating the control valve at will, a suction pipe communicating with the interior of said middle buck at the rear thereof having a further control valve and being connected to an outside source of suction, a second operating member connected to the further control valve for operating the latter at will, an overhanging hollow supporting member including a pipe rigidly mounted on said frame and terminating in a downwardly-directed open end spaced above the top of the middle buck, an enclosed blast chamber fixed beneath the middle buck upon the frame and having an upwardly-directed neck portion or chimney directed toward said middle buck, a flexible porous bag connected to the neck portion for ballooning the waist of the pants to be pressed and having a pair of upwardly-projecting back portions adapted to be inserted in the leg portions of said pants, a steam radiator in the blast chamber connected to the source of steam supply, a fan chamber connected to one portion of the blast chamber, a motor-driven fan rotatable in the fan chamber for driving air past the radiator to the neck portion and the flexible bag, control means for controlling the flow of heated air to said flexible bag including a group of pivotally mounted slats arranged in a vertical series between the motor-driven fan and the radiator, an operating bar interconnecting the slats to open and close them simultaneously, a manually-operated member supported in the blast chamber with an externally accessible handle for manipulating the member at will, a lever on the latter member connected to said operating bar for opening or closing said slats from the last-mentioned handle, a pair of manually-adjusted waist-holding means shiftably mounted adjacent said neck portion for engaging within the forward and rear edges of the waist of said pants, an upwardly-directed steam nozzle in the blast chamber within the neck portion or chimney thereon, a pipe connecting the steam nozzle to the outside steam-supply source, a valve between the latter pipe and said steam nozzle, a valve-operating member on said valve, a manually-

19

operated member connected to the valve-operating member and extending through said chimney into accessible position upon the forward portion of the presser, a cable in the hollow supporting member having the upper end thereof projecting through said downwardly-directed end and terminating in at least one suspension ring for suspending therefrom one or more pants hangers and thereby suspending the pants in inverted position with the two legs thereof disposed on the opposite sides of said middle buck in effective position to be pressed against the latter by said side bucks, a shaft rotatably supported upon a portion of the blast chamber, a lever on one end of the shaft connected to the 15

20

other end of said cable, and an operating member fixed upon the other end of said shaft for shifting said cable in said hollow support and thereby raising or lowering the suspension ring above the middle buck.

GEORGE G. A. LAUZON.
